M. GRISWOLD, JR.
SOCKET SUPPORT FOR ELECTRIC SAD IRONS.
APPLICATION FILED MAY 6, 1908.

918,533.

Patented Apr. 20, 1909.

UNITED STATES PATENT OFFICE.

MATTHEW GRISWOLD, JR., OF ERIE, PENNSYLVANIA, ASSIGNOR TO GENERAL ELECTRIC COMPANY, A CORPORATION OF NEW YORK.

SOCKET-SUPPORT FOR ELECTRIC SAD-IRONS.

No. 918,533.

Specification of Letters Patent. Patented April 20, 1909.

Application filed May 8, 1908. Serial No. 431,255.

To all whom it may concern:

Be it known that I, MATTHEW GRISWOLD, Jr., a citizen of the United States, residing at Erie, in the county of Erie and State of Pennsylvania, have invented certain new and useful Improvements in Socket-Supports for Electric Sad-Irons; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to socket apparatus for electric sad-irons, and has for its object the providing of mechanism on the socket, and upon the sad-iron handle adapted to be engaged when the socket is put in place on the sad-iron, whereby the upper end of the socket is firmly supported against lateral movement.

The features of my invention are herein-after fully set forth and described, and illustrated in the accompanying drawings, in which:

Figure 1 is a view in elevation of an electric sad-iron embodying my invention. Fig. 2 is a view in elevation of a portion of an electric sad-iron showing the socket being attached thereto. Fig. 3 is a side view in elevation of the sad-iron handle showing a hook thereon. Fig. 4 is a top or plan view of the electric socket, showing a perforated lug thereon adapted to slip over the hook on the sad-iron handle. Fig. 5 is a rear end view of the sad-iron showing the electric terminals with which the socket engages.

In these drawings A is the body of the

sad-iron, B B' the handle supports, C the handle, D the electric heater, d d the electric terminals connecting therewith, and E the socket, all of which are of usual and ordinary construction. On the handle support B under the nut b securing the handle C to the handle support B, I place a washer F having an upwardly projecting hook f thereon, and on the upper part of the socket E, I secure a projection H having an opening h therein, adapted to slip over the hook f as the socket E is put in place and thus firmly support the upper end of the socket E from any lateral movement. It is obvious that if desired I can secure the hook to the socket and make the projection on the washer F with an opening to engage the hook on the socket with equal facility.

In operation the slipping of the socket E down upon the socket-terminals d d operates to simultaneously engage the projection H with the hook f.

Having thus described my invention so as to enable others to construct and utilize the same, what I claim as new and desire to secure by Letters-Patent is

In an electric sad-iron, a handle, a hook on one of the handle supports, electric connecting studs on said iron, an electric connection socket adapted to engage the connection studs on the sad-iron, and a perforated lug on said connection socket adapted to engage the hook on the handle support substantially as set forth.

In testimony whereof I affix my signature, in presence of two witnesses.

MATTHEW GRISWOLD, JR.
